UNITED STATES PATENT OFFICE.

JAMES H. COFFMAN, OF COLUMBUS, OHIO, ASSIGNOR TO THE WISCONSIN CHAIR COMPANY, OF PORT WASHINGTON, WISCONSIN.

DESIGN FOR A BENT-WOOD CHAIR-SEAT.

SPECIFICATION forming part of Design No. 31,951, dated December 5, 1899.

Application filed September 22, 1899. Serial No. 731,367. Term of patent 7 years.

To all whom it may concern:

Be it known that I, JAMES H. COFFMAN, a citizen of the United States, residing at Columbus, in the county of Franklin and State

5 of Ohio, have invented and produced a new and original Design for Bent-Wood Chair- Seats, of which the following is a specification, reference being had to the accompanying drawings, showing a part thereof.

10 In said drawings, Figure 1 is a top plan view of a bent-wood chair-seat, showing my design. Fig. 2 is a longitudinal vertical section of the same, these two views being deemed necessary to fully illustrate my design.

15 The leading feature of my design for bent- wood chair-seats consists in the peculiar surface formation of said seat, which may be described as follows:

20 The upper edge 6 of the design between the two side points 7 of the outer edge takes the form of a portion of the radius of a large circle. Each outer edge of my design, starting from the point 7, proceeds downward in a straight line to the point 8, thence on an irregular curve to the point 9. From the point 25 9 it proceeds in a substantially straight line

to a point 10 and from there is carried down and around on an irregular curve to the point 11, which is the opposite end of the design from the point 7.

30 In Fig. 2 the edge in cross-section, which is taken on line $a a$ in Fig. 1, it will be seen starts from the upper edge 6 of my design and proceeds to a point opposite point 9 in an irregular curve. Section-lines running parallel with line $a a$, if taken at intervals between $a a$ and the outer edge between the points 7 and 11, would proceed on an irregular curve from the upper edge 6 to points in line with point 9, and the curve of each section-line would diminish as the lines reached the outer edge between 7 and 11.

35 Having thus described my invention, what I claim is—

40 The design for a bent-wood chair-seat substantially as shown and described.

Signed by me at Port Washington, Wisconsin, this 23d day of August, 1899.

JAMES H. COFFMAN.
